UNITED STATES PATENT OFFICE.

FRANK P. D'ARCY, OF KALAMAZOO, MICHIGAN.

SEAT-CUSHION STRUCTURE.

1,129,337.

Specification of Letters Patent. Patented Feb. 23, 1915.

Application filed February 26, 1914. Serial No. 821,152.

To all whom it may concern:

Be it known that I, FRANK P. D'ARCY, a citizen of the United States, residing at Kalamazoo, in the county of Kalamazoo and 5 State of Michigan, have invented certain new and useful Improvements in Seat-Cushion Structures, of which the following is a specification.

This invention relates to improvements 10 in seat cushion structures.

The objects of this invention are: First, to provide an improved seat cushion in which the entire sewing thereon can be done upon a sewing machine. Second, to provide 15 an improved structure in which the parts can be quickly and easily assembled and the springs placed and secured therein with a minimum amount of hand labor.

Further objects and objects relating to 20 details and economies of construction will definitely appear from the detailed description to follow.

I accomplish the objects of my invention by the device and means described in the 25 accompanying specification. The invention is clearly defined and pointed out in the claims.

A structure constituting a preferred embodiment of my invention is shown in the 30 accompanying drawing forming a part of this specification, in which:

Figure I is a perspective view of a structure embodying my invention. Fig. II is a bottom plan view of said structure. Fig. 35 III is an enlarged sectional view on the line 3—3 of Figs. II and VI, showing in detail the engagement of the retaining clip with the spring supporting bar and the auxiliary bottom frame. Fig. IV is an enlarged perspective view showing in detail 40 the engagement of the tongues at the end of one of the spring supporting bars with the auxiliary bottom frame and the border wire of the set of springs. Fig. V. is a plan view of a blank from which the clip shown in Fig. III is made. Fig. VI is a bottom plan view of a modified form of 45 my invention. Fig. VII is an enlarged sectional view on the line 7—7 of Fig. VI, showing in detail the connection between the front end of one of the spring supporting bars and the wooden cross bar. Fig.

VIII is a perspective view on an enlarged scale of a modification showing a different arrangement of tongues engaging the auxiliary bottom frame and the border wire. 55

In the drawing, similar reference characters refer to similar parts throughout the several views, and the sectional views are taken looking in the direction of the little 60 arrows at the ends of the section lines.

Considering the numbered parts of the drawing, 1 is the top portion of the seat which is padded in any suitable manner. 2 is a strip secured to said cushion portion at 65 its upper edge and forming the side wall portions of said seat. 3 is the auxiliary bottom frame which is made of two sections detachably connected together, one of said sections being disposed in the pocket formed 70 at the lower edge of the side wall portion 2. This pocket is formed by folding the lower edge of said strip up over the wire forming the auxiliary frame and stitching it. All this is clearly shown and described 75 in my co-pending application, Serial No. 821,152 filed the 26th day of February, 1914. The front portion of the top 1 is also brought downwardly, as clearly shown in Fig. 1, and the cross bar section of the 80 auxiliary bottom frame 3 is similarly disposed in a pocket formed in the lower edge of said portion.

It will be seen that the top portion and the side wall portion together form a chamber in which a set of springs 5 is disposed. 85 This set of springs is provided with a border wire 6, which, in the preferred form of my invention, extends entirely around the lower edge of said set of springs and 90 the springs are carried by spring supporting bars 7—7. The ends of the spring supporting bars 7 are split to form three tongues. The outer tongues 10, 10 are pointed, pass through the fabric of the side wall portion 2 and are bent downwardly and wrapped around the auxiliary bottom frame 3. These tongues 10, 10 pass between the border wire 6 and the auxiliary bottom frame 3. The central tongue 11 passes over 100 the border wire 6 and is wrapped around the same. In this manner it will be seen that the spring supporting bars 7 are securely fastened to the auxiliary bottom.

frame 3 and to the border wire 6 of the set of springs.

To connect the outer spring supporting bars 7 with that part of the border wire and 5 of the auxiliary bottom frame which lies parallel to said supporting bars, I provide a plurality of clips 12 on either side of the set of springs. These clips 12 are made from a blank which is provided at one end 10 with a pointed tongue 13. The body of the blank, just to the rear of the base of the tongue, is provided with a pair of parallel slits so as to form the portion 14. It will thus be seen that when the portion 14 between the parallel slits is struck up it will 15 form an eye or passage. These clips are disposed on the border wire 6 with said wire 6 passing through the eye or passage formed by the struck up portion 14. The 20 body portion 12 of said clip extends transversely of the spring supporting bar 7, beneath the same, and is wrapped around said bar so as to conform to the curvature thereof. The tongue 13 of said clip is passed 25 through the fabric forming the side wall portion 2 and is bent downwardly and back, being wrapped around the auxiliary bottom frame 3. In this manner those portions 30 of the auxiliary bottom frame and the border wire 6 lying parallel to the spring supporting bars are securely connected to them.

In Fig. VI I have shown a modified form of my invention in which the auxiliary bottom frame of the spring structure is formed 35 of two sections, one of which is a wire frame 3 such as shown in Fig. II, while the other section is formed by a wooden cross bar 4 to which the bottom edge of the front portion of the seat is tacked. In this modification, the set of springs 5 has a border wire 6 which extends around three edges thereof 40 and the ends of which are bent laterally at the front of said set so as to extend parallel with the wooden cross bar 4. In this modification, the front end of the spring supporting bars 7 have a channel 8 struck up 45 therein, and the front ends of said bars are flattened so as to lie flat on the wooden cross bar 4. The spring supporting bars are so 50 disposed that the channel 8 receives the ends of the border wire 6 lying parallel to said cross bar 4 and the front ends of said supporting bars are secured to the cross bar by means of nails 9. The other ends of the 55 supporting bars are secured to the auxiliary bottom frame and the border wire in the manner which I have heretofore described. The clips 12 which are also provided are identical with those which I have already 60 described in reference to Fig. II.

In Fig. VIII I have shown a modification in which I make use of a different arrangement of tongues on the ends of the spring supporting bars 7. In this modification, the

outer tongues 16, 16 are passed between the 65 auxiliary bottom frame 3 and the border wire 6 and are bent upwardly and wrapped around said border wire 6. The central tongue 15 is pointed and passes over the border wire 6 through the fabric of the side 70 wall portion 2 and is bent downwardly and wrapped around the border wire 6 and the auxiliary bottom frame 3. In this manner the end of the spring supporting bar 7 is securely connected to the border wire and 75 auxiliary bottom frame.

From the description of the parts given above, the construction of this device should be very readily understood. The seat is formed with the side wall portion in two 80 sections and with an auxiliary bottom frame comprising two sections detachably connected together. In this respect it embodies part of the invention described and claimed in my co-pending application, Serial No. 85 821,152, filed Feb. 26, 1914. To construct this seat, auxiliary bottom frame sections are provided at the lower edge of the side wall strips or portions as shown in my co-pending application, and the set of springs is placed 90 within the chamber formed by said top portion and said side wall portions. Clips 12 are strung upon the border wire 6, said wire passing through the eye or passage formed by the struck up portion 14, with the body 95 portion of said clip extending transversely of the spring supporting bars 7 adjacent said border wire. The tongues 13 are then forced through the fabric of the side wall portion 2 and brought down and wrapped around said auxiliary frame. The body portion of the clip 12 passes underneath the bar 7 and is wrapped around said bar to conform to the curvature thereof as clearly 100 shown in Fig. III. The tongues on the 105 ends of the supporting bar are wrapped around the border wire 6 and the auxiliary bottom frame 3 so as to engage the same as clearly shown in Fig. IV. In this manner 110 the set of springs is securely held in position and the parts of the seat cushion structure are securely held together. All this can be done with a minimum amount of 115 manual labor. This makes the cost of producing the springs very slight as compared with other structures known in the art.

The structure shown in Fig. VI is produced in the same way except that the wooden cross bar 4 with the lower front portion of the seat attached thereto is 120 brought beneath the front end of said spring supporting bars and said bars are nailed to said cross bar by means of the nails 9 with the front ends of the border wire 6 engaging in the channels 8.

I am aware that the particular embodiment of my invention which I have here set forth is susceptible of considerable vari-

ation without departing from the spirit of my invention and, therefore, I do not wish to be restricted to the same. However, I have found that this form is to be preferred and, therefore, I desire to claim the same specifically as well as broadly as indicated by my appended claims.

Having thus described my invention, what I claim as new and desire to secure by Letters Patent is:

1. In a structure of the class described, the combination of a top portion, a frame connected with said top portion, a set of springs supporting said top portion and provided with a border wire around the edge thereof, said springs being carried by supporting bars provided with tongues projecting from the ends thereof, one of said tongues extending between said border wire and said frame and being wrapped around said frame, other tongues being wrapped around said border wire, all coacting substantially as described for the purpose specified.

2. In a structure of the class described, the combination of a top portion, side wall portions secured at their upper edges to said top portion, an auxiliary bottom frame comprising two sections detachably connected together, a set of springs, disposed in the chamber formed by said top portion and said side wall portions, and having a border wire around the edge thereof, the springs being carried by spring supporting bars, said bars having a tongue at each end thereof wrapped around said border wire, and another tongue at each end thereof wrapped around said auxiliary bottom frame, all coacting substantially as described for the purpose specified.

3. In a structure of the class described, the combination of a top portion, side wall portions secured at their upper edges to said top portion, an auxiliary bottom frame comprising a plurality of sections carried by the lower edge of said side wall portions, a set of springs disposed in the chamber formed by said top portion and said side wall portions, said springs being carried by supporting bars, and means provided on the ends of said supporting bars for securing said bars to said auxiliary bottom frame, all coacting substantially as described for the purpose specified.

4. In a structure of the class described, the combination of a top portion, side wall portions, an auxiliary bottom frame comprising two sections carried by the lower edges of said side wall portions, a set of springs disposed in the chamber formed by said top portion and said side wall portion, and having a border wire around the edges thereof, the springs being carried by spring supporting bars, a plurality of clips con-

necting said spring supporting bars with the adjacent portions of said border wire and auxiliary bottom frame, each clip comprising a body portion embracing said spring supporting bar and extending transversely thereof, an eye through which the border wire passes and a tongue embracing the auxiliary bottom frame, all coacting substantially as described for the purpose specified.

5. In a structure of the class described, the combination of a top portion, side wall portions, an auxiliary frame carried by the lower edges of said side wall portions and comprising two sections, a set of springs disposed in the chamber formed by said top portion and said side wall portions, said springs being carried by spring supporting bars, and a plurality of clips extending transversely of said spring supporting bars and having a tongue embracing said auxiliary bottom frame, the body portion of said clip embracing said spring supporting bar whereby the outer supporting bars are connected with the adjacent portions of the auxiliary bottom frame.

6. In a structure of the class described, the combination of a top portion, side wall portions, an auxiliary bottom frame comprising a plurality of sections carried by the lower edges of said side wall portions, a set of springs disposed in the chamber formed by said top portion and said side wall portions, said springs being carried by spring supporting bars, means connecting the ends of said bars to the sections of said auxiliary bottom frame, and clips connecting the outer bars to the adjacent portions of the auxiliary bottom frame, all coacting substantially as described for the purpose specified.

7. In a structure of the class described, the combination of a top portion, side wall portions, an auxiliary bottom frame comprising two sections carried by the lower edges of said side wall portions, a set of springs disposed in the chamber formed by said top portion and said side wall portions, and being provided with a border wire around the edges thereof, said springs being carried by spring supporting bars, the ends of said bars being provided with a plurality of tongues extending between said auxiliary bottom frame and said border wire and embracing said border wire, and a tongue embracing the auxiliary bottom frame and said border wire, all coacting substantially as described for the purpose specified.

8. In a structure of the class described, the combination of a top portion, side wall portions, a two part bottom frame carried by the lower edges of said side wall portions, a spring supporting structure carried by

4
said two part bottom frame and securing the parts thereof together, and a set of springs disposed in the chamber formed by said top portion and said side wall portions, 5 and carried by said spring supporting structure, all coating substantially as described and for the purpose specified.

In witness whereof, I have hereunto set my hand and seal in the presence of two witnesses.

FRANK P. D'ARCY. [L. S.]
